UNITED STATES PATENT OFFICE

ALFRED W. BRUCE, OF NEW YORK, N. Y.

LOCOMOTIVE BOILER

Original application filed January 11, 1927, Serial No. 160,330. Divided and this application filed November 19, 1927. Serial No. 234,346.

The invention is disclosed in the present application, which is a division of the application filed January 11, 1927, Ser. No. 160,330.

The invention relates, generally, to boilers of the locomotive type, and, specifically, to those of that type in which the sides of the fire box and combustion chamber are formed of a plurality of water tubes, instances of which are exemplified in the patents of J. 5 M. McClellon, No. 1,580,063, April 6, 1926, and Alfred W. Bruce, No. 1,624,656, April 12, 1927. The present invention is particularly directed to the adaptation of a boiler of the type specified, for operation under 10 comparatively high steam pressure, and to effecting a reduction of the weight and dimensions of the boiler to a substantial extent. A characteristic feature of the invention is the application of separate circulation systems for the fire box and for the barrel of the 15 boiler.

The improvement claimed is hereinafter fully set forth.

In the accompanying drawings: Figure 1 20 is a vertical longitudinal central section through a boiler embodying the invention; Fig. 2, a plan view thereof; Fig. 3, a vertical transverse section, the right hand half being taken on the line III, III of Fig. 1, and the 25 left hand half on the line IIIa, IIIa, thereof; Fig. 4, a similar section, the right hand half being taken on the line IV, IV of Fig. 1, and the left hand half on the line IVa, IVa, thereof; and, Fig. 5, a view, partly in longitudinal 30 central section and partly in elevation, illustrating the circulation of water in the boiler.

In the practice of the invention, referring 35 descriptively to the specific embodiment thereof which is herein exemplified, the improved locomotive boiler thereof comprises three main sections; the fire box, A, the boiler barrel, B, through which extends a plurality of fire tubes, 3b, and the smoke box, C. The mud ring, 2, of the fire box, is hollow, 40 and forms the bottom support of a plurality of water tubes, 3, which are set closely together, forming the side walls of the fire box, and are connected, at their upper ends, with a drum, 4, which extends horizontally and 45 forwardly over the fire box, and which has

steam communication adjacent to its forward end, with a header, 13, at the rear end of the barrel, B, and is open at its forward end, which is connected to an upwardly extending junction piece, 4a, having a manhole in its 55 top, closed by a cover, 4b. Water circulation pipes, 22, extend from the top of the header, 13, to the mud ring, 2, of the fire box.

A water circulation pipe, 4c, leads from the lower end of the junction piece to the forward portion of the barrel, and a deflecting plate, 4d, extends downwardly and rearwardly below its opening into the barrel. A steam receiving chamber, 4e, (one or more), of smaller diameter than the drum, extends forwardly from the upper end of the junction piece, to or near the rear of the smoke box, C, its forward end being supported on, and fitted to slide in, a bearing, 4h, secured to the top of the smoke box, thereby providing for longitudinal expansion of the chamber, 4e. A steam collecting chamber, 4f, having a plurality of perforations in its top, is located in the steam receiving chamber, 4e, adjacent to its top and to its forward end. By this 75 construction, the steam is separated as far as possible from the water, and it is delivered from the chamber, 4f, through a pipe, 4g, to the throttle valve, 16, and thence, through pipes, 17, to the superheater, 18, or to the 80 engine cylinders, as the case may be. As shown in Fig. 1, the steam delivery pipes, 17, are connected by slip joints, to the superheater, 18, (equivalently to the cylinder direct supply pipes) so as to permit free movement of the steam delivery chamber, 4e.

A diaphragm plate, 23, is located in the rear portion of the barrel, B, adjacent to its axial plane, and extends across the same, from a vertical sheet, 23a, therein, through 90 which the fire tubes, 3b, of the barrel pass, to within a short distance from its front flue sheet. Feed water is supplied to the barrel through a feed pipe, 23b, provided with the usual check valve, and located a short distance forward of the vertical sheet, 23a.

In the operation of a boiler of the construction above described, there is, as indicated by the line having a plurality of arrow heads, 95 in Fig. 5, a single continuous positively 100

guided circulation of water through the water spaces of the barrel and fire box, the water in the barrel being thereby constantly stirred up, instead of being comparatively undisturbed as in ordinary constructions. The water supplied to the barrel through the feed pipe, 23b, moves forwardly through the compartment thereof below the diaphragm plate, 23, to the forward portion of the barrel; thence rearwardly through the compartment of the barrel above said plate, to the header; thence downwardly through the circulation pipes, 22, to the mud ring, 13, thence, through the side water tubes, to the drum, 4, and thence, through the circulation pipe, 4c, to the forward portion of the barrel. The circuit continuously repeats itself through the members stated.

The invention claimed as new and desired to be secured by Letters Patent is:

1. In a boiler of the locomotive type, the combination of a throttle valve; a fire box section the sides of which are formed of water tubes; a hollow mud ring communicating with the lower ends of said water tubes; a cylindrical boiler shell section connected to and extending forwardly from the fire box section; a plurality of fire tubes in said cylindrical boiler shell section; a drum extending forwardly from the rear of the fire box section, said drum communicating with the upper ends of the water tubes thereof; a conduit establishing communication between the drum and the forward portion of the cylindrical boiler shell section; means connecting the upper portion of the barrel and the mud ring to afford communication therebetween; a steam receiving chamber communicating with the forward end of the drum and extending forwardly thereof; and a steam delivery connection through which steam passes from the steam receiving chamber to the throttle valve.
2. In a boiler of the locomotive type, the combination of a throttle valve; a fire box section the sides of which are formed of water tubes; a hollow mud ring communicating with the lower ends of said water tubes; a cylindrical boiler shell section connected to and extending forwardly from the fire box section; a plurality of fire tubes in said cylindrical boiler shell section; a drum extending forwardly from the rear of the fire box section, said drum communicating with the upper ends of the water tubes thereof; a junction fitting communicating with the forward end of the drum; a conduit connecting said junction fitting with the forward portion of the cylindrical boiler shell section; a heater at the rear end of the cylindrical boiler shell section communicating therewith; a conduit establishing communication between the upper portion of the header and the mud ring; a steam receiving chamber communicating with the junction fitting and extending for-

wardly therefrom; a steam collecting chamber located in the steam receiving chamber and communicating therewith; and a steam delivery connection, extending from the steam collecting chamber, through the steam receiving chamber, to the throttle valve.

3. In a boiler of the locomotive type, the combination of a throttle valve; a fire box section the sides of which are formed of water tubes; a hollow mud ring communicating with the lower ends of said water tubes; a cylindrical boiler shell section connected to and extending forwardly from the fire box section; a plurality of fire tubes in said cylindrical boiler shell section; a drum extending forwardly from the rear of the fire box section, said drum communicating with the upper ends of the water tubes thereof; a header at the rear end of the cylindrical boiler shell section communicating therewith; a conduit connecting the upper portion of the header with the mud ring; a steam receiving chamber disposed forwardly of the drum and in open communication therewith; means for delivering steam from said chamber to the throttle valve; and a conduit communicating with the forward end of the drum and the forward end of the cylindrical boiler shell.

4. In a boiler of the locomotive type, the combination of a throttle valve; a fire box section the sides of which are formed of water tubes; a hollow mud ring communicating with the lower ends of said water tubes; a cylindrical boiler shell section connected to and extending forwardly from the fire box section; means connecting the upper portion of the boiler shell with the mud ring to afford communication therebetween; a plurality of fire tubes in said cylindrical boiler shell section; a drum extending forwardly from the rear of the fire box section, said drum communicating with the upper ends of the water tubes thereof; means connecting said drum to the shell section a steam receiving chamber rigidly connected to the forward end of said drum and extending to the forward end of the cylindrical boiler shell section; a bearing in which the forward end of the steam receiving chamber is supported with the capacity of free movement to compensate for longitudinal expansion and contraction; and means for delivering steam from the steam receiving chamber to the throttle valve, comprising a conduit rigidly secured to said receiving chamber and having a slip joint in its length adapted to compensate for longitudinal expansion and contraction of the chamber.

5. In a boiler of the locomotive type, the combination of a fire box, the sides of which are formed of water tubes; a hollow mud ring, communicating with the lower ends of said water tubes; a barrel, connected to, and extending forwardly from, the fire box; a plurality of fire tubes in said barrel; a drum,

extending forwardly from the rear of the fire box, said drum communicating with the upper ends of the water tubes thereof; a vertical sheet, fixed in the rear lower portion of 5 the barrel, through which sheet a plurality of the fire tubes are passed; a horizontal diaphragm plate, projecting forwardly from said sheet, between rows of fire tubes; a feed water connection, leading into the barrel, 10 forward of said sheet; a circulation pipe, adapted to convey water from the upper portion of the barrel to the mud ring, in rear of said sheet; and a circulation pipe, leading from the drum to the forward portion of the 15 barrel.

6. In a boiler of the locomotive type, the combination of a throttle valve; a fire box section the sides of which are formed of water tubes; a hollow mud ring communicating with the lower ends of said water tubes; a cylindrical boiler shell section connected to and extending forwardly from the fire box section; a plurality of fire tubes in said cylindrical boiler shell section; a drum extending 20 forwardly from the rear of the fire box section, said drum communicating with the upper ends of the water tubes thereof; a conduit establishing communication between the drum and the forward portion of the cylindrical boiler shell section; means establishing 25 communication between the barrel and the mud ring; a steam receiving chamber communicating with the forward end of the drum and extending forwardly thereof; a steam delivery connection through which steam passes from the steam receiving chamber to the throttle valve; a vertical partition wall disposed between the ends of the cylindrical boiler shell section and extending from 30 the bottom part way to the top thereof; a horizontal partition extending from the upper portion of the vertical partition forwardly adapted to provide communication 35 between the shell section portions above and below the horizontal partition; and a feed water connection, leading into the shell section, forward of said vertical partition.

7. In a boiler of the locomotive type, the combination of a throttle valve; a fire box section the sides of which are formed of water tubes; a hollow mud ring communicating with the lower ends of said water tubes; a cylindrical boiler shell section connected to and extending forwardly from the fire box 50 section; a plurality of fire tubes in said cylindrical boiler shell section; a drum extending forwardly from the rear of the fire box section, said drum communicating with the upper ends of the water tubes thereof; a junction fitting communicating with the forward end of the drum; a conduit connecting said junction fitting with the forward portion of the cylindrical boiler shell section; a header at the rear end of the cylindrical boiler shell 55 section communicating therewith; a conduit

establishing communication between the upper portion of the header and the mud ring; a steam receiving chamber communicating with the junction fitting and extending forwardly therefrom; a steam collecting chamber located in the steam receiving chamber and communicating therewith; a steam delivery connection, extending from the steam collecting chamber, through the steam receiving chamber, to the throttle valve; a vertical 70 partition wall disposed between the ends of the cylindrical boiler shell section and extending from the bottom part way to the top thereof; a horizontal partition extending from the upper portion of the vertical partition 75 forwardly adapted to provide communication between the shell section portions above and below the horizontal partition; and a feed water connection leading into the shell section forward of said vertical partition. 80

8. In a boiler of the locomotive type, the combination of a throttle valve; a fire box section the sides of which are formed of water tubes; a hollow mud ring communicating with the lower ends of said water tubes; a cylindrical boiler shell section connected to and extending forwardly from the fire box section; a plurality of fire tubes in said cylindrical boiler shell section; a drum extending 90 forwardly from the rear of the fire box section, said drum communicating with the upper ends of the water tubes thereof; a header at the rear end of the cylindrical boiler shell section communicating therewith; a conduit 95 connecting the upper portion of the header with the mud ring; a steam receiving chamber disposed forwardly of the drum and in open communication therewith; means for delivering steam from said chamber to the throttle valve; a conduit communicating with the forward end of the drum and the forward end of the cylindrical boiler shell; a vertical partition wall disposed between the ends of the cylindrical boiler shell section and extending 100 from the bottom part way to the top thereof; a horizontal partition extending from the upper portion of the vertical partition forwardly adapted to provide communication between the shell section portions above and below the horizontal partition; and a feed water connection, leading into the shell section forward of said vertical partition. 105

9. In a boiler of the locomotive type, the combination of a fire box section, the sides of which are formed of water tubes; a hollow mud ring communicating with the lower ends of said water tubes; a cylindrical boiler shell section connected to, and extending forwardly from the fire box; a plurality of fire tubes in said boiler shell section; a drum extending forwardly from the rear of the fire box and communicating with the upper ends of the water tubes thereof; a conduit establishing 120 communication between the forward end of the 125

the drum and the forward end of the boiler shell section; a deflector within the boiler shell section opposite the mouth of the conduit leading into the boiler shell section, said deflector being adapted to deflect rearwardly of the boiler shell section water delivered into the boiler shell section by said conduit; a header between the boiler shell section and the fire box section; means for establishing communication between the mud ring and the upper portion of the header; and a steam receiving chamber extending forwardly of and communicating with the drum.
